TRANSPARENT STAMP POCKET FOR
ALBUM MOUNTING

Paul Zimmer, Venlo, Netherlands

Application September 21, 1937, Serial No. 164,976
In Germany September 22, 1936

1 Claim. (Cl. 40—159)

This invention relates to a pocket of transparent material, for instance cellulose derivatives and the like free from fibres, for storing and sticking postage stamps into albums or the like, the pocket having a tongue adapted to be turned over upon the rear side of the pocket and designed to be stuck on a leaf of the album, the pocket ensuring not only that the postage stamp is stored so that it cannot be damaged, but which 5 further permits of removing the postage stamp or prevents removing of the same without reducing the possibility to inspect the stamp.

Pockets of transparent material formed by a sheet are known. It has already been proposed 15 to employ, for forming a pocket, a sheet of double width which is folded along a line parallel to the side edge. By folding over and sticking-on small edge-strips onto the back side of the folded over half of the sheet, the pocket is produced. An 20 upper edge strip folded onto the rear side serves as flap for sticking the pocket onto the leaf of the album. As only this edge strip is stuck onto the leaf of the album, the pocket is always open at the upper end. By means of a pocket of this 25 type a postage stamp can be removably fixed on an album-leaf so that also its rear side can be inspected.

Arrangements have also become already known for fixing postage stamps in an album which consist of a transparent strip wound off from a roll. The strip has two edges folded over to the rear side. One of these folded over edges is serrated. The serrations engage over the postage stamp. When sticking into the album the pocket with 30 the postage stamp, the corner teeth of the serrated edge are fixed on the leaf. By lifting the portion of the strip serving as cover, the rear side of the postage stamp can be inspected. With this arrangement the stamps do not have the 35 required hold, they could be pulled out in lateral direction. Besides this, it seems doubtful whether, the pocket shape being lacking, the strip warps or not during the unwinding from the roll. It is also not possible to attach the 40 postage stamp in the album so that it can be removed or cannot be removed, but observed as 45 desired.

Pockets for postage stamps with a tongue for sticking-on the open pocket have also become 50 known.

According to the invention the edge extensions on the front side of the pocket designed to be folded over onto the back of the blank and forming the pocket when they are joined, are smaller 55 than the front side of the pocket and the tongue

is formed by an incised strip of the upper flap to be folded over onto the rear side of the pocket, said flap being gummed, same as the tongue, on the side facing the album leaf. Hereby it is attained that it is possible to accommodate the 5 postage stamp in the pocket so that it cannot be removed or so that it can be removed, it being, however, always possible to inspect the rear side of the postage stamp.

The pockets are preferably produced in sets 10 of different sizes, so that the pockets can be bought for any current size of postage stamps.

An embodiment of the invention is illustrated, by way of example, in the accompanying drawing, in which

Fig. 1 shows in top plan view the blank for the pocket.

Fig. 2 shows how the blank is folded to form a pocket in which the postage stamp is removably stored.

Fig. 3 shows the folded pocket according to Fig. 2.

Fig. 4 illustrates the folding of a pocket from which the postage stamp cannot be removed.

Fig. 5 shows the folded pocket according to Fig. 4.

In all figures the pocket is shown in rear view. The blank 1 for the pocket is made of cellulose derivatives free from fibres. The blank 1 has at each edge an extension 2, 3 and 4 respectively. 30 A tongue 5 is cut in the upper extension 2 and this upper extension 2 is gummed on the side facing the album leaf, whereas the extension 3 is gummed only at the points which are overlapped by the extensions 4.

When folding the blank to a pocket which is designed to permit subsequent removal of the postage stamp, first the extension 3 is folded over onto the back of the blank 1, whereupon the extensions 4 are folded over onto the extension 3 and portions of the back of the blank 1 in being stuck onto the extension 3. The extension 2 is then folded over onto the rear side without sticking on, so that the pocket remains open at the upper end. The gummed outer side of extension 2 serves to stick the pocket onto the album leaf. If a stamp is to be removed or

inserted, the pocket is folded on line 6 so that the back of the pocket is placed against the album leaf and the open end of the pocket made 45 accessible.

If the pocket has to be folded so that it is not possible to remove the postage stamp, the extension 3 is first folded over onto the back of the blank 1, whereupon the extension 2 is folded 50

over onto the back of blank 1 and the extensions 4 are then folded over onto the extensions 2 and 3 of blank 1 laterally of the tongue 5 and stuck onto the extensions 2 and 3. The pocket is then closed. The tongue 5 serves for sticking the pocket onto the album leaf and admits of turning over the pocket so that the back of the postage stamp becomes visible, the liberated cut out portion of the extension 2 resulting in the 10 tongue 5 permitting of examining the gumming of the postage stamp.

The pocket may evidently have perforations for facilitating subsequent tearing open of the pocket.

15. The pockets are preferably sold preliminarily folded but the extensions not stuck together.

I claim:

A pocket for storing postage stamps and for

sticking them in albums, wherein the pocket is made of transparent material, such as cellulose derivatives free from fibres, said pocket formed from a blank having a rectangular central portion, a flap on each edge of the central portion, one of said flaps being cut to form a tongue between the sides thereof, all of said flaps being of lesser area than the central portion, and said flaps being foldable over the central portion with selected faces of the flaps gummed, the flap carrying the tongue and the diametrically opposite flap being first folded over the central portion and the other pair of edge flaps being folded over the first folded flaps and gummed thereto laterally of the tongue and the outer face of the 10 tongue being gummed for album mounting.

PAUL ZIMMER.
